CONTINUOUS-VERTICAL COKING RETORT
OVEN

Paul Van Ackeren, Essen, Germany, assignor, by
mesne assignments, to Koppers Company,
Pittsburgh, Pa., a corporation of Delaware

Application April 8, 1936, Serial No. 73,238
In Germany February 3, 1934

2 Claims. (Cl. 202—251)

The invention relates to continuous vertical chamber ovens or retorts for the production of gas and coke, and in particular to vertical chamber ovens or retorts of such a design, that in the upper part of the coking chamber there is provided a metallic suspension frame, extending from the oven roof into the interior of the chamber and adapted to feed the raw coal to be coked directly into the high temperature zone of the chamber, whilst the distillation gases produced in the coking chamber are drawn-off from the space between said coal feeder and the chamber wall.

During the operation of such vertical chamber ovens, or retorts, it has been found as a disadvantage, that certain constituents of the distillation gases have condensed in the gas collecting space surrounding the coal feeder. Especially at the cooler parts of the metallic feeder, filled with cold coal, and at the chamber roof such condensable substances deposit and decompose partially. By the formation of new deposits on the more or less decomposed condensates, the free section of the gas collecting space and of the suction pipe respectively will be choked up gradually. In order to avoid such stoppages, in the gas path, the deposits have to be removed from time to time by means of rods or the like, whereby the comparatively low expense for attending the continuous verticals is considerably increased.

The main object of my present invention is to provide improvements in the upper part of said vertical chamber oven or retorts, so as to prevent stoppages (due to condensation of decomposable gas constituents) within the path of the distillation gases.

My present invention consists principally in that the metallic coal feeder and the chamber roof are equipped with a cover of heat insulating material inside the chamber in such a manner, that the temperature in the gas collecting space and at the walls will always be higher than the dew point of the distillation gases with regard to condensable hydrocarbons contained therein.

Furthermore, the present invention has for its object to provide a new and useful design of the metallic coal feeder, arranged in the upper part of the chamber for feeding the raw coal to be coked directly into the hot chamber zone, said feeder being constructed according to the invention in such a way, that the heat insulating refractory cover may be attached safely to the metallic body of the feeder.

Still further objects of my invention will be

understood readily from the following description of a preferred embodiment of my present invention.

On the drawing, Figure 1 is a vertical longitudinal section through a part of a continuous vertical chamber oven, according to my invention.

Figure 2 is a vertical cross section according to line II—II of Fig. 1 and Fig. 3 is a horizontal section according to line III—III of Fig. 1 in an enlarged scale.

Figure 4 is a vertical cross section through one part of Fig. 1, in an enlarged scale.

Figure 5 is a vertical cross section according to line V—V of Fig. 4.

The continuous vertical chamber oven shown on the drawings is provided with a coking chamber 4, formed by refractory brick walls 20. The coking chamber 4 is closed on the top by a cover plate 7, having a central oblong opening in which the coal feeder 2 is arranged. The feeder 2 has a projecting frame 5, interlocking a sand seal 6, provided on the cover plate 7. The upper part of the feeder 2 is connected with the outlet 1 of a coal storage hopper not shown on the drawing. Closable openings 17 are provided in the enlarged body of the feeder 2 and may be used for introducing pushing rods or the like into the feeder pipe.

At the left front side of the chamber roof, the gas ascension pipe 10, leading to the hydraulic main 10a, is connected to the cover plate 7 of the coking chamber 4, whilst on the right front side a cleaning opening 21 is provided.

The lower side of the chamber roof plate 7 and eventually also the upper side thereof is covered with a heat insulating material 16, such as highly porous refractories. Likewise, the feeder 2 is fitted with a cover of heat insulating material on its part projecting into the coking chamber. The cover of the roof plate 7 and of the feeder 2 is constructed in such a way, that the gas collecting space 8, 8a provided in the upper part of the chamber 4 is formed only by walls of heat insulating material.

The heat insulating cover of the coal feeder 2 is fully illustrated in Figure 3. The body of the feeder consists of two cast iron frames, 19, 19a connected with one another by hinges 12, said frames being slightly convex on their length sides in order to prevent the warping of the cast iron body when heated. The outside of the frame 19, 19a is provided with a row of dovetailed ribs 13, between which are inserted plates 14 consisting of heat insulating refractory material. At the lower part of the frame 19, 19a a horizontal fram-

ing rib 15 is provided upon which the plates 14 are supported.

The coking chamber 4 is indirectly heated in the usual manner, gas and air are burning in 5 vertical heating flues 3, arranged in the walls of the chamber 4. The heating media burning upwards in the flues 3 and the waste gases respectively enter the horizontal channels 3a, provided on the upper end of the flues 3 and from 10 there to heat exchangers, for instance regenerators or recuperators, corresponding to the heating system of the oven.

As illustrated in Figure 2, the coal feeder 2 reaches up to the heating flue zone of the chamber walls, so that the coal fed into the chamber 15 will be quickly heated and coked. The slope formed by the charge below the outlet of the feeder inside the chamber is marked on the drawing with 11 and 11a, respectively.

20 As shown in Figure 1, it may be advisable to line the ascension pipe 10 also with heat insulating refractories 10b in order to prevent any condensation of vapors and inconvenient deposits.

I claim:

25 1. Continuous-vertical coking retort oven comprising a retort chamber adapted to be fed continuously at its top with coal to be coked and having refractory heating walls external thereto for externally applying coking heat to coal in said chamber through the heating walls therefor: a metal cover forming a suspension frame arranged to cover the top of said chamber between the same and the atmosphere and having distillate gas offtake means in the same and a metallic 30 coal feeder chute suspended from said frame so as to extend down from the metal cover into the top of the chamber in spaced relation to the refractory walls therefor for delivering the coal to be coked into a high temperature zone at a 35 distance from the top of the chamber leaving a gas collecting and off-flow space around the coal feeder so that the distillation gases produced in the chamber may be drawn off from the top of the coking charge to the distillate offtake through a free space between the coal feeder and the 40 walls of the top of the chamber; the outer surfaces of the sides of said coal feeder and the inner surface of the metallic cover being covered with a lining of heat insulating porous refractory material on the inside of the chamber and so as to prevent heat from being conducted through the sides of the coal feeder for absorption by coal therein and through the metallic cover for radiation into the atmosphere and thereby maintain the temperature of gas in the gas collecting and off-flow space and the walls forming the same always higher than the dew 45 point of the distillation gases with regard to condensable hydrocarbons; said coal feeder comprising a row of spaced upright dovetail ribs on the outer surface of its sides and said lining comprising plates of the heat insulating refractory 50 material inserted between the ribs and provided with dovetail projections fitting the dovetail ribs on the coal feeder and a horizontal rib at the lower part of the coal feeder between the upright ribs.

absorption by coal therein and through the metallic cover for radiation into the atmosphere and thereby maintain the temperature of gas in the gas collecting and off-flow space and the walls forming the same always higher than the 5 dew point of the distillation gases with regard to condensable hydrocarbons.

2. Continuous-vertical coking retort oven comprising a retort chamber adapted to be fed continuously at its top with coal to be coked and 10 having refractory heating walls external thereto for externally applying coking heat to coal in said chamber through the heating walls therefor: a metal cover forming a suspension frame arranged to cover the top of said chamber between 15 the same and the atmosphere and having distillate gas offtake means in the same and a metallic coal feeder chute suspended from said frame so as to extend down from the metal cover into the top of the chamber in spaced relation to the refractory walls therefor for delivering the coal to be coked into a high temperature zone at a 20 distance from the top of the chamber leaving a gas collecting and off-flow space around the coal feeder so that the distillation gases produced in 25 the chamber may be drawn off from the top of the coking charge to the distillate offtake through the free space between the coal feeder and the walls of the top of the chamber; the outer surfaces of the sides of said coal feeder and the inner surface of the metallic cover being covered with a lining of heat insulating porous refractory material on the inside of the chamber and so as to prevent heat from being conducted through the sides of the coal feeder for absorption by coal therein and through the metallic cover for radiation into the atmosphere and thereby maintain the temperature of gas in the gas collecting and off-flow space and the walls forming the same always higher than the dew 30 point of the distillation gases with regard to condensable hydrocarbons; said coal feeder comprising a row of spaced upright dovetail ribs on the outer surface of its sides and said lining comprising plates of the heat insulating refractory 35 material inserted between the ribs and provided with dovetail projections fitting the dovetail ribs on the coal feeder and a horizontal rib at the lower part of the coal feeder between the upright ribs.

PAUL VAN ACKEREN.
